UNITED STATES PATENT OFFICE

JASPER DERRY, OF MEDFORD, MASSACHUSETTS, ASSIGNOR TO ANDREW TERKELSEN,
OF NEWTON, MASSACHUSETTS

PRESS

Application filed April 11, 1930. Serial No. 443,390.

This invention relates to presses and is in the nature of a modification of the invention shown and described in a prior application filed October 4, 1928, Serial No. 310,340.

5 In common with the invention disclosed and claimed in said prior application, the present invention has for its general objects to provide a compact, mechanically operated press wherein the closing movement of the press elements is automatically controlled and limited by the pressure exerted upon the work irrespective of the size and character of the latter, and wherein said pressure is maintained after the stopping of the press, notwithstanding subsequent volumetric changes in the work, to provide means for automatically stopping the opening movement of the press elements when they have been separated by a predetermined but variable 15 amount, to provide means whereby the predetermined pressure exerted upon the work can be conveniently adjusted and varied in accordance with the requirements, and to provide means whereby the operation of the 20 press can be manually, as well as automatically, controlled.

More particular objects of the present invention are to provide an electrical control for presses of this type, thereby greatly simplifying the mechanism, and to provide means for automatically stopping the movement of the movable press element toward the cooperating element upon failure, for any reason, of said cooperating element to exert 25 its normal reaction to the pressure exerted by said movable element.

The foregoing and other objects of the invention, together with means whereby the latter may be carried into effect, will best be understood from the following description of a preferred embodiment thereof illustrated in the accompanying drawings, but it will also be understood that the particular construction and adaptation described and shown have been chosen for purposes of exemplification merely, and that the invention, as defined by the claims hereunto appended, may be otherwise embodied without departure 50 from the spirit and scope thereof.

In said drawings:

Fig. 1 is a front elevation of a press embodying the invention,

Fig. 2 is a horizontal section taken substantially on the line 2—2 of Fig. 1, 55

Fig. 3 is a wiring diagram of the electrical connections,

Fig. 4 is a detail vertical sectional view of the electromagnetic reversing switch.

Fig. 5 is a detail view of the solenoid brake. 60

Referring particularly to Figs. 1 and 2, the relatively movable press elements comprise a bed 15 and a ram 16 which may carry suitable complementary dies 17 or other devices in accordance with the nature of the work 65 to be performed by the press.

The bed 15 is supported by four parallel, upright posts or rods 18 to which it is secured in any suitable manner, as by means of nuts 19 engaging threaded end portions 70 19a on said posts.

The posts or rods 18 are guided for vertical longitudinal movement in suitable bearings 20 and 21 in the frame 14, the latter being adapted to receive the reduced portions 10 at the lower ends of said posts and constituting abutments upon which said posts normally rest. 75

Surrounding the posts or rods 18 below the bearings 20 are heavy coil springs 22 80 interposed between flanges 23 formed on the frame and collars 24 in engagement with the threaded lower ends 25 of said posts and secured in adjusted position thereon by set screws 12. The collars 24 cooperate with 85 the rods 18 whereby the springs 22 may be placed and held under a predetermined initial compression. With this arrangement it will be seen that when the press elements approach one another, so as to engage the work therebetween at opposite sides, the pressure of the ram against the work and bed will be transmitted to the springs 22 which will yield to permit movement of the bed and displacement of the posts to an extent 90 determined by the pressure applied and consequent compression of the springs. 95

The ram 16 is carried by a double rack 27 guided in the frame 14 and engaged at 100 opposite sides by two pairs of pinions 28

fast on parallel shafts 29 journaled in the frame and also having fast thereon intermeshing gears 30 connecting the pinions of each pair. One gear 30 of each pair of pinions meshes with a pinion 31 fast on a shaft 32 journaled in the frame and having fast thereon a gear 33. The gear 33 meshes with a pinion 34 fast on a shaft 35 journaled in the frame and having fast thereon a gear 36. The gear 36 meshes with a pinion 37 fast on a shaft 38 which is journaled in a gear casing 39 carried by the frame. The shaft 38 has fast thereon a worm gear 40 which meshes with a worm 41 on the armature shaft 42 of an electric motor M suitably supported on the frame, said shaft 42 being likewise journaled in the gear casing 39.

The motor M, which is preferably an alternating current motor of the three-phase type, is supplied with electrical energy from three feed lines L_1 , L_2 , and L_3 . (See Fig. 3.) In accordance with the invention, the operation of the motor is controlled to move the ram 16 in one direction to exert the predetermined pressure upon the work and in a reverse direction to release the pressure and separate the press elements. For this purpose the passage of the current through the feed lines to the motor is controlled by a magnetic reversing switch R which throws the motor across the line.

The reversing switch R (see Figs. 3 and 4) is provided with two triple-pole, magnetically-operated contactors a and b which are wired as shown in Fig. 3 so that when one contactor is closed the motor operates in one direction and when the other contactor is closed the motor operates in the reverse direction. Each contactor is closed by an operating coil 61 or 71 which is controlled by a separate circuit connected with the feed lines, both circuits being controlled by a manually operated, three-button control station C having an "up" switch 80, a "down" switch 81, and a "stop" switch 82. The "up" and "down" switches are of the "momentary contact" type, being normally open while the "stop" switch is normally closed. Each circuit is further controlled by a limit switch A or B which is operated automatically to stop the motor and thus limit the movement of the ram in either direction. The limit switches are normally closed.

The contactor a (see particularly Fig. 4) comprises fixed and movable members, the latter being pivotally mounted on the frame 112 of the reversing switch, and being provided with an armature 110 which cooperates with the coil 61 when the latter is energized to close said contactor. An electric interlock e , operated by the contactor a and provided for the purpose of closing its operating circuit, comprises a movable member 111 yieldingly mounted in the movable member of said contactor and fixed members 113 se-

cured to the frame 112. The contactor b likewise comprises fixed and movable members, the latter being pivotally mounted on the frame 112 and being provided with an armature 114 which cooperates with the coil 71 when the latter is energized to close said contactor. An electric interlock f operated by the contactor b and provided for the purpose of closing its operating circuit comprises a movable member 115 yieldingly mounted in the movable member of said contactor and fixed members 116 secured to the frame 112. The contactors are mechanically interlocked by a bar 117 pivoted intermediate its ends to the frame 112, said ends being secured by links 118 to each of the movable members of said contactors. This construction prevents both contactors being closed at the same time. The contactors and the electric interlocks are normally open, but when either contactor is closed the interlock for completing its operating circuit is also closed while the other interlock is open, thus permitting the closing of only one circuit at a time.

The circuit for controlling the reversing switch to operate the motor to move the ram in a forward (in the present instance, upward) direction is shown by light full lines in Fig. 3. By pressing the button to momentarily close the "up" switch 80, the current coming in through the line L_2 will flow through wire 60, operating coil 61, wires 62 and 63, "up" switch 80, wire 64, limit switch A, wire 65, "stop" switch 82, wires 66 and 67, and out through line L_3 .

This causes the operating coil 61 to be energized and the contactor a to be closed, which connects the feed lines L_1 , L_2 and L_3 with the motor as shown in Fig. 3, to drive it in a direction to move the ram 16 forwardly, or upwardly, towards the bed of the press. As this contactor is closed, its interlock e is closed, and the current may now flow through line L_2 , wire 60, coil 61, wire 62, interlock e , wires 68 and 64, limit switch A, wire 65, "stop" switch 82, wires 66 and 67 and line L_3 , or it may flow through line L_1 , wire 69, interlock e , wire 62, coil 61, wire 60 and line L_2 , depending upon the polarity of the feed lines.

The circuit just described keeps the operating coil 61 energized regardless of the polarity of the feed lines and thus insures an uninterrupted movement of the press ram in a forward or upward direction until the limit switch A is automatically opened or the "stop" switch 82 is previously opened by the operator in case of an emergency.

When a predetermined pressure between the press elements has been reached and the limit switch A automatically opened, as hereinafter explained, the contactors will assume an opened position and, as was previously stated, both interlocks e and f will

be opened. To release the pressure and separate the press elements, the operator presses the button to momentarily close the "down" switch 81. This closes a circuit indicated in light dot and dash lines in Fig. 3 for controlling the reversing switch R to operate the motor in a reverse direction for the above purpose. At this time the current will flow, through line L_2 , wires 60 and 70, operating coil 71, wires 72 and 73, "down" switch 81, wire 74, limit switch B, wire 75, "stop" switch 82 and to the line L_1 through the wires 66 and 67 which are common to both operating circuits.

15 The operating coil 71 thus energized closes the contactor δ which connects the feed lines with the motor to throw the latter "across the line" and thus reverse it. As this contactor is closed, its interlock f is closed, and 20 the current may now flow through line L_2 , wires 60 and 70, coil 71, wire 72, interlock f , wires 78 and 74, limit switch B, wire 75, stop switch 82, wires 66 and 67 and line L_1 , or it may flow through line L_1 , wires 76 and 77, interlock f , wire 72, coil 71, wires 70 and 60 and line L_2 , depending upon the polarity of the feed lines. The circuit just described keeps the operating coil 71 energized regardless of the polarity of the feed lines and thus insures an uninterrupted movement of the press ram in a reverse direction until stopped by the automatic opening of the limit switch B or the manual opening of the "stop" switch 82.

35 It will be understood that the "up" switch 80 and "down" switch 81 are manually operated to start the press in accordance with the requirements, and that the "stop" switch 82 may also be manually operated to stop 40 the press at any time in case of emergency. The limit switches A and B are automatically operated by the moving parts of the press and to this end each is provided with an operating or trip arm 26 each of which normally 45 occupies a position to close its respective switch but which is capable of operation to open said switch. The trip arm 26 of the limit switch B is disposed in the path of movement of a lug 43 adjustably secured, as by a 50 set screw 44, to a rod 45 projecting upwardly from the ram 16, said trip arm being engaged by said lug to open the limit switch B when the ram 16 has descended to its lowermost position determined by the adjusted position 55 of said lug on the rod 45. The trip arm 26 of the limit switch A is disposed in the path of movement of a projection 46 on a slide 47 held in a clamp 48 carried by one of the posts 18 and is engaged by said projection to open the limit switch A when said post moves upwardly under the yielding action 60 of the springs 22. The slide 47 is adjustably carried by the clamp 48 and is preferably provided with a suitable scale 49, where- 65 by the extent of yielding movement of the

springs 22, and consequently the pressure upon the work, necessary to open the limit switch A may be conveniently varied. The trip arm 26 of the limit switch A is also operable to open said switch by a slide 50 vertically movable in guides 51 on an upright frame member 52 which supports the hand control and limit switches, said slide 50 having an angular upper end 53 disposed in the path of movement of the lug 43 and adapted 70 to be engaged thereby upon excessive upward movement of the ram 16.

The operation is as follows:

In Fig. 1 the ram 16 is shown in a mid-position in its path of travel. Assuming 80 that the ram is moving upwardly at this time, this movement will be continued until the dies 17 have closed upon the work and have exerted thereon a pressure sufficient to cause the springs 22 to yield and the posts 18 to 85 move upwardly. When the limit of this movement, and consequently of the pressure exerted upon the work, as predetermined by the adjustment of the slide 49 in the clamp 48, has been reached, the projection 46 engages the trip arm 26 of the limit switch A, thereby opening said switch and stopping the movement of the ram. The work is thereupon resiliently held under the predetermined pressure by the springs 22 which, in 90 case of any shrinkage of the work, can expand slightly to exert a follow-up pressure thereon. To release the pressure and separate the press elements, the "down" switch 81 is momentarily closed, thereby reversing 100 the motor M as above described. The ram 16 is thereupon moved downwardly until the lug 43 engages the trip arm 26 of the limit switch B, opening the latter switch and again 105 stopping the motor M and the movement of the ram.

In the event of breakage of the springs 22, or stripping of the threads on the upper ends 110 19a of the posts 18, or the failure of the nuts 19, or other condition preventing the bed 15 from exerting its normal reaction to the upward pressure of the ram, the consequent abnormal upward movement of the ram will cause the lug 43 to engage the angular end 53 of the slide 50, thereby opening the limit 115 switch A and automatically stopping the press.

The armature shaft 42 is preferably provided with a brake 54 normally applied by a spring 55 (Fig. 5) but held released against 120 the tension of said spring when the motor is running by a solenoid 56 in a shunt circuit 57 (Fig. 3) between the feed lines L_1 and L_2 .

Means are preferably provided for indicating the pressure exerted by the press upon the work, said means, as shown in Fig. 1, comprising a dial plate 120 secured by a bracket 121 to the upper end of one of the posts 18 and having a suitable graduated scale. Journalled in the dial plate 120 is an 125

arbor 122 carrying at one end a pointer 123 movable over the scale on said dial plate. Secured to the opposite end of the arbor 122 is a pinion 124 which cooperates with a rack 125 carried by the frame member 52. It will be seen that the pressure exerted upon the work, as determined by the compression of the springs 22 and consequent upward movement of the bed 15 and posts 18, will be indicated on the dial 120 by the pointer 123 due to the movement of the bracket 121 relative to the frame member 52.

I claim:

1. In a press, the combination with relatively movable press elements, of a resilient element associated with one of said press elements and subjected to the pressure exerted therebetween, means for relatively moving said elements toward one another, comprising a rack carried by one of said press elements, a train of gearing, and an electric motor, means including an electric circuit for controlling said moving means, and means controlled by the yielding movement of said resilient element and consequently by the amount of said pressure for controlling said electric circuit and thereby stopping the relative movement of said elements when a predetermined pressure has been reached.
2. In a press, the combination with relatively movable press elements, of an element subjected to the pressure exerted between said press elements and displaceable thereby amounts varying with the amount of said pressure, means for relatively moving said elements toward one another, comprising a rack carried by one of said press elements, a train of gearing, and an electric motor, means including an electric circuit for controlling said moving means, and means actuated by a predetermined movement of said displaceable element for controlling said electric circuit and thereby stopping the relative movement of said press elements.
3. In a press, in combination, a resiliently supported bed, a ram, means for moving said ram toward and from said bed, comprising a rack carried by said ram, a train of gearing, and an electric motor, means including an electric circuit for controlling said moving means, and means operatively connected with both said ram and said bed for controlling said circuit to stop the movement of said ram upon a predetermined movement of either of said elements.
4. In a press, in combination, a bed, a resilient support for said bed, a ram, means for moving said ram toward said bed, comprising a rack carried by said ram, a train of gearing, and an electric motor, and means controlled by the pressure exerted between said bed and ram for controlling said moving means and for stopping the movement of said ram when a predetermined pressure has been reached, said last named means being also rendered

operative to stop said movement upon failure of said bed to exert its normal reaction to said pressure.

5. In a press, in combination, a bed, a resilient support for said bed, a ram, means for moving said ram toward said bed, comprising a rack carried by said ram, a train of gearing, and an electric motor, means including an electric circuit for controlling said moving means, and means rendered operative by failure of said bed to exert its normal reaction to the pressure of said ram for controlling said circuit to stop said moving means.

6. In a press, in combination, a bed, a resilient support for said bed, a ram, means for moving said ram toward said bed, comprising a rack carried by said ram, a train of gearing, and an electric motor, means including an electric circuit for controlling said moving means, and means controlled by the pressure exerted between said bed and ram for controlling said electric circuit and thereby stopping the movement of said ram when a predetermined pressure has been reached, said last named means being also rendered operative to stop said movement upon failure of said bed to exert its normal reaction to said pressure.

7. In a press, in combination, a bed, a resilient support for said bed, a ram, means including a rack carried by said ram, a train of gearing and an electric motor for moving said ram toward said bed, and means rendered operative by failure of said bed to exert its normal reaction to the pressure of said ram for breaking the circuit to said motor.

8. In a press, in combination, a resiliently supported bed, a ram, means for moving said ram toward said bed, comprising a rack carried by said ram, a train of gearing, and an electric motor, means including an electric circuit for controlling said moving means, a member movable with said bed, a clamp carried by said member, a slide adjustably mounted in said clamp and having an engaging portion, and a member engaged by the engaging portion of said slide when said bed yields for controlling the electric circuit and thereby stopping the movement of said ram by said moving means.

9. In a press, in combination, a resiliently supported bed, a ram, means including a rack carried by said ram, a train of gearing, and an electric motor for moving said ram toward and from said bed, automatic means operatively connected with both said ram and said bed for opening the circuit to said motor and stopping the movement of said ram upon a predetermined movement of said ram toward and away from said bed, and manually operable means for closing the circuit to said motor for starting the movement of said ram in the opposite direction upon operation of said automatic means.

10. In a press, in combination, a frame,

a bed resiliently supported on said frame, a ram carried on a rack movable in said frame, pinions engaging said rack for moving said ram toward and from said bed, a train of gears connected with said pinions, an electric motor for driving said gears, limit switches carried on a member secured to said frame and having trip arms engaged by engaging means carried by both said ram and said bed for opening the circuit to said motor and stopping the movement of said ram upon a predetermined movement of said ram toward and away from said bed, and manually operable means for closing the circuit to said motor and starting the movement of said ram in the opposite direction upon operation of said automatic means.

11. In a press the combination of a bed, a ram, springs for supporting said bed against the pressure of said ram, mechanism for moving said ram toward and away from said bed, comprising a rack carried by said ram, a train of gearing, an electric motor, different electrical circuits to said motor for controlling the movement of said ram in either direction, manually operable switches for completing each of said circuits to move said ram in either direction and opening said completed circuit to stop said ram at any position, and means for automatically opening said completed circuit to stop said ram upon a predetermined movement of said ram in either direction.

12. In a press the combination of a bed, a ram, springs for supporting said bed against the pressure of said ram, mechanism for moving said ram toward and away from said bed, comprising a rack carried by said ram, a train of gearing, an electric motor, different electrical circuits to said motor for controlling the movement of said ram in either direction, manually operable switches for completing each of said circuits to move said ram in either direction and opening said completed circuit to stop said ram at any position, a limit switch in each of said circuits, and a stop device to control each limit switch and automatically open said completed circuit and thereby stop said ram upon a predetermined movement of said ram in either direction.

13. In a press the combination of a bed, a ram, springs for supporting said bed against the pressure of said ram, mechanism for moving said ram toward and away from said bed, comprising a rack carried by said ram, a train of gearing, an electric motor, different electrical circuits to said motor for controlling the movement of said ram in either direction, manually operable switches for completing each of said circuits to move said ram in either direction and opening said completed circuit to stop said ram at any position, a limit switch in each of said circuits, a stop device to control each limit

switch and automatically open said completed circuit and thereby stop said ram upon a predetermined movement of said ram in either direction, and an auxiliary stop device rendered operative by failure of said bed to exert its normal resistance to the pressure of said ram for controlling its respective limit switch and thereby limit the movement of said ram toward said bed.

In testimony whereof I affix my signature. 73
